TUBULAR EXTRUDED SHAPE

John E. Ganoe, New Kensington, Pa., assignor to
 Aluminum Company of America, Pittsburgh,
 Pa., a corporation of Pennsylvania

Application May 17, 1933, Serial No. 671,567

4 Claims. (Cl. 156—14)

This invention relates to improvements in tubular shapes of irregular cross section and particularly to improvements in such tubular shapes as are used for window and screen frames and the like.

Difficulties encountered in obtaining uniformity of product in such shapes by extruding the tubular portion as a closed section have led to the adoption of the practice of extruding shapes 10 in open form and subsequently closing the section to produce the final tubular form. The closing operation is usually performed by drawing through a die or dies of suitable form.

An object of my invention is to provide tubular shapes such as are used for screen frames, window frames, and the like, which are more resistant to deformation and of better appearance than previous shapes. A further object is the provision of such improved shapes which can be 20 readily produced by simple metal working operations. Other objects will be apparent from the following specification and the drawing in which;

Fig. 1 shows a shape as extruded and embodying one form of my invention;

Fig. 2 shows the extruded shape of Fig. 1 in its completed form;

Fig. 3 shows a modification of my invention as extruded;

Fig. 4 shows the extruded shape of Fig. 3 in its completed form.

The shape shown as extruded in Fig. 1, and in its finished form in Fig. 2, is typical of the shapes used in the manufacture of screen frames. As extruded the shape consists essentially of a base portion 1 and a cantilevered portion 2 of angular shape provided with a depending leg 3, the base portion 1 being provided with an upstanding leg 4, and a second and longer upstanding leg 5. The opening between legs 3 and 4 is essential to provide support for the portion of the extrusion die extending interiorly of the base 1, cantilevered portion 2 and legs 3 and 4.

The particular section chosen for illustration is adapted to provide a supporting frame for a window screen or the like, the screen cloth being fixed in the groove partially formed by the leg 5 by some suitable fastening means.

The process of extrusion consists in forcing a body of metal, usually heated, through a die of suitable cross-section, and the metal as extruded takes substantially the same form as the die opening. After the shape shown in Fig. 1 has been produced by this process the cantilevered portion 2 is folded down either by drawing the shape

through a die or dies or in some other convenient manner. The legs 3 and 4 are thus brought into abutting relationship, forming a longitudinal seam along the tubular portion of the finished shape.

Previous shapes produced in this manner have had the abutting faces of the legs flat or substantially flat. When such shapes are closed it has been found difficult to obtain a structure in which the faces coincide exactly. This results in an irregular and non-uniform shape. To correct this difficulty I provide the legs 3 and 4 with a plurality of complementary inclined surfaces 6 and 7, to insure positive alignment of the parts. Such surfaces can form a simple V, as illustrated in Figs. 1 and 2, or can have a flat portion 8, as shown in Figs. 3 and 4, which while slightly different in form are otherwise the same as the first two figures.

I have found the shapes so formed to be substantially more resistant to deformation than shapes without such inclined complementary surfaces. While more complex positioning means have been tried, they are no more effective for the purpose than the simple structure shown and described, and only lead to complicated tool construction and fabrication difficulties.

I have illustrated and described specific forms of my invention, but it will be understood that I do not wish to be limited thereto, since various modifications and changes will readily suggest themselves to those skilled in the art and many such modifications may be made without departing from the scope of my invention as defined in the appended claims.

I claim:

1. A shape of extruded metal having a tubular portion provided with a longitudinal seam formed by two self-aligning abutting portions each having a plurality of inclined plane complementary surfaces.

2. An extruded metal shape for screen frames and the like, consisting of a hollow tubular portion having at least one substantially flat side wall and another side wall of greater thickness substantially perpendicular thereto, an integrally formed continuation of said flat side wall extending beyond said perpendicular side wall and provided with a substantially perpendicular upstanding leg which is substantially parallel with the thicker side wall for at least a part of its length, the said thicker side wall of said tubular portion having a longitudinally extending seam formed by two parts abutting to form said wall, each of said parts having a plurality of inclined

plane surfaces engaging complementary inclined plane surfaces on the other of said parts.

3. An open extruded metal shape adapted to be drawn closed to form a hollow tubular member, said shape in open form comprising separated adjacent portions provided with complementary inclined surfaces, and said inclined surfaces providing surface contacting aligning means for the adjacent portions when the shape is drawn closed.
4. In an open extruded metal shape adapted to

be drawn closed to form a hollow tubular member, a seam comprising inclined surfaces formed on the faces of adjacent separated portions of said open shape, said inclined surfaces being complementary in form and adapted to provide alignment of the separated portions on drawing the shape closed, said inclined surfaces providing only superposed surface bearing therebetween.

JOHN E. GANOE. 10
